UNITED STATES PATENT OFFICE.

CHARLES H. OCUMPAUGH, OF ROCHESTER, NEW YORK.

RAZOR.

1,013,805.

Specification of Letters Patent.

Patented Jan. 2, 1912.

Application filed February 15, 1910. Serial No. 544,112.

To all whom it may concern:

Be it known that I, CHARLES H. OCUMPAUGH, a citizen of the United States, residing at Rochester, in the county of Monroe and State of New York, have invented certain new and useful Improvements in Razors, of which the following is a specification.

This invention relates to improvements in razors, of the safety type. Heretofore with razors of this character, it was necessary to adjust the parts, to obtain a "coarse" shave as is customary "the first time over", and then again adjust the parts before 15 "going over the second time" in order to obtain a "close" shave. This in many instances amounted to guessing, in determining whether or not the parts were properly set to secure the desired result.

According to my present invention, I provide two guards, each being arranged in different relative positions with regard to the edge of the blade, so that with one adjustment, with one side of the razor a 25 "coarse" shave can be obtained, while with the other, a "close" shave may be secured. And what is of great importance is that when shaving one can always tell which edge is the one he has been using.

I also provide as part of my invention a blade of new construction which overcomes many of the objections heretofore offered against flat blades.

The invention further comprehends improvements in the specific details of construction and arrangement of parts, to be hereinafter referred to and particularly pointed out in the claims.

In the drawings:—Figure 1 is a perspective view of the preferred form of my invention. Fig. 2 is a transverse section. Fig. 3 is a perspective view of the same, the parts being separated. Fig. 4 is a perspective view of a slightly different form of 45 the invention, the parts being separated and include a modification of the blade. Fig. 5 is a still further modification of the blade. Fig. 6 is a perspective view of a modified form of guard.

Referring particularly to Figs. 1, 2, and 3,

1 indicates a combined holder and guard provided with a convex upper surface 2; a handle 3; and a central perforation 4, extending from the convex surface through and into the handle. The guard portion of 55 the holder 1, is formed with a series of outwardly extended teeth 5, along one edge, to coöperate with a cutting blade 6. The cutting blade 6, is preferably formed from a thin sheet of metal of uniform thickness, 60 and is permanently held curved in cross section either by means of a flange 6¹ struck up from the blade as shown in Fig. 3, or by doubling the metal back in itself as 6² in Fig. 5, or if desired by using separate stiffening means shown as 14¹ in Fig. 4. The upper guard, or clamping member 8, is curved in cross section, and is formed on one edge only with a series of outwardly projecting teeth 9, and a depending threaded rod 10. The teeth 70 9¹ at the ends of the clamping member may be bent downwardly to position the blade on the combined holder and guard 1. Or the flange 6¹ on the blade 6 may be used as positioning means for the blade when the 75 blade is placed on the holder. In assembling this form of my invention, the blade 6, is placed on the concave surface 8¹, of the combined clamping member and guard in the manner usual in razors of this type. 80 The rod 10, of the clamping member or guard 8, being passed through the blade perforation 7, and into the opening 4, and engages the threaded portion of a locking member 11 of the handle 3, which when 85 operated draws the parts together, hence securely binding the cutting blade between the clamp and holder. When so assembled it will be observed the teeth 5, are below the cutting edge of one side of the blade, while 90 the teeth 9 are on top of the opposite edge of said blade. This arrangement of the guard teeth, furnishes a razor which without adjustment will enable a person to go over his face and obtain either a coarse or 95 close shave as may be desired, depending on which edge of the razor is used. I arrange the guard teeth on the bottom of one edge of the blade to obtain a "once over" or "coarse" shave, and the teeth of the clamp 100

on top of the blade on the other or opposite edge of the blade for securing a "second time over" or "smooth" shave.

My invention is not limited to the construction shown in Figs. 1, 2, and 3, as it will be obvious many minor changes may be made without departing from the spirit of the improvement. For instance in my copending application Serial No. 413,672, I show a razor blade having a permanent cross sectional curvature, formed by embossings, which coöperate with positioning lugs on the holder.

In Fig. 4, I have shown a cutting blade 13, having end stiffening lugs 14¹, and in this case perforations 13¹ which coöperate with the lugs or bosses 15 on the holder. The holder is formed on but one edge with the guard teeth, so also is the clamp, these teeth however, being arranged to extend in opposite direction as before described.

In lieu of the screw and handle connected as shown in Figs. 1 and 4, I may employ a lock indicated at 17, in Figs. 4 and 6, which is essentially the same as that shown in the before mentioned application.

In place of either set of the guard teeth, I may use a plain bar 18, indicated in Fig. 6, and is of the type shown in the copending application referred to, the only difference being, that in the present invention it is on but one side of the holder.

The invention is not in any wise limited to a blade having a fixed cross sectional curvature, as a blade of the flexible characteristic can be used just as well.

Broadly stated this invention comprehends a single guard provided with means on one edge to coöperate with the blade at the top, and a single guard having means opposite to the means on the top guard to coöperate with the opposite edge of said blade, for the sole purpose of enabling a person to shave either close, or coarse, without the tedious and annoying adjusting of parts. And it also enables the person to know definitely which edge of the blade he is supposed to be shaving with, overcoming the confusion incident to the ordinary double guard razor heretofore on the market, when the razor is momentarily laid down.

The invention also comprehends a rigid blade of sheet metal, having its rigidity maintained by increasing the thickness of the two ends of the blade, thus leaving the remainder of the blade free from the embossing, etc., as in my copending application No. 413,989.

60 I am aware that I have shown in a copending application Serial #410,989 a razor blade having an integral flange at its end extending at right angles to the cutting edge

for stiffening the blade, but this particular feature I did not claim in said copending application having reserved it for this application.

What I claim is:

1. In a safety razor, the combination of a two edged razor blade, a holder to support the blade and provided on one edge with a guard, located adjacent one edge of said blade, a clamp fitting over the blade and provided on its edge with a guard located adjacent the opposite edge of said blade, the two guards being on opposite sides of the blade, and each being in a different relative position with respect to the cutting edge than the position of the other guard with respect to the other cutting edge, and means for securing the clamp blade and holder together.

2. In a safety razor, the combination of a curved two edged razor blade having reinforcing means at its ends to permanently curve it in cross section, a curved holder provided on one of its edges with a guard located adjacent one edge of said blade, a curved clamp fitting over the blade and provided on its edge with a guard located adjacent the opposite edge of said blade, the two guards being on opposite sides of the blade and each in a different horizontal plane, and each being in a different relative position with respect to the cutting edge than the position of the other guard with respect to the other cutting edge, and means for securing the clamp blade and holder together.

3. In a safety razor, the combination of a curved two edged razor blade formed with an opening, a curved holder to support the blade and provided on one edge with a guard located adjacent one edge of said blade, said holder having an opening, a handle having a threaded opening, a curved clamp fitting over the blade and provided with a screw which passes through the openings in the blade and holder and engages the threads in the opening in the handle, and said clamp having a guard located adjacent the opposite edge of said blade, the two guards being on opposite sides of the blade, and each being in different relative position with respect to the cutting edge than the position of the other guard with respect to the other cutting edge.

4. In a safety razor, the combination of a two edged razor blade, a holder to support the blade and provided on one edge with a guard located adjacent one edge of said blade, a clamp fitting over the blade and provided on its edge with a guard located adjacent the opposite edge of said blade, the two guards being on opposite sides of the blade, and each being in a different relative

position with respect to the cutting edge than the position of the other cutting edge, means for securing the clamp blade and holder together, and lugs extending from 5 the clamp to engage the blade to hold the latter and clamp in relative position while the securing means are being tightened.

In testimony whereof I affix my signature in presence of two witnesses.

CHARLES H. OCUMPAUGH.
